FLOOR BRUSH

Filed Aug. 29, 1927

UNITED STATES PATENT OFFICE

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT

FLOOR BRUSH

Application filed August 29, 1927. Serial No. 216,099.

My invention relates more especially to that type of brushes employed for cleaning floors and similar surfaces, and an object of the invention, among others, is the production of a brush of this type that shall be particularly efficient in operation, and that shall have novel features of construction whereby the brush may be produced in a simple and economical manner.

10. One form of brush embodying the invention and in the construction and use of which the objects herein set out, as well as others, may be attained, is illustrated in the accompanying drawings, in which—

15. Figure 1 is a top view of my improved floor brush.

Figure 2 is a side view of the same.

Figure 3 is a detail view, scale enlarged, in cross section through one of the frame members illustrating the manner of securing the brush material therein.

Figure 4 is a view in section on a plane denoted by the dotted line 4—4 of Figure 1.

Figure 5 is a view in section on a plane denoted by the dotted line 5—5 of Figure 1, but showing a modified construction of the frame members with the brush material secured therein.

Figure 6 is a view in section on a plane denoted by the dotted line 6—6 of Figure 5.

Figure 7 is a detail view showing the plate from which the handle attaching bracket is formed.

A brush embodying the invention forming the subject matter of this application is comprised of a back of frame-like construction in which the cleaning element, usually composed of fibrous material, is secured, this frame including a plurality of channeled members from which the cleaning material projects, said channeled members being secured together by tie pieces and spacers to provide a rigid structure, and a bracket to which a handle is secured is also attached to the frame in a manner to strengthen it.

In the accompanying drawings the numerals 8 and 9 designate two channeled members, of substantially the same shape, except as to size, these members being preferably of oblong shape and endless in construction with

rounded ends and one of the members being located within the boundaries of the other and evenly spaced therefrom on all sides, as illustrated in Figure 1 of the drawings. Each of these members is provided with a channel 10 formed by bending the metal into U-shape in cross section, and the fibres or other elements comprising the cleaning material are doubled at about their lengthwise center and folded over an anchoring rod 11 that extends for at least the whole length of the brush material within the channeled member, the lips 12 of said channeled member being compressed closely against the cleaning material 13 to firmly and securely hold it within the channeled member.

The tie pieces and spacers 14, each of which possesses both of these functions, are preferably formed from sheet metal and each is bent into proper shape to provide recesses 15, which recesses are formed to correspond to the cross sectional shape of the channeled members 8—9. These tie pieces are fixed to the frame by springing them over the channeled members, and they may be located at such distances apart along the channeled members as may be desired, in the structure herein shown there being two of these tie pieces and spacers located one near each end of the frame, and as shown in Figure 1 of the drawings. Any other suitable means for securing the tie pieces in place may be employed.

The bracket for securing the handle to the structure is formed from a single plate of sheet metal 16 that is stamped to shape and comprising side bars 17, from which clips 18 project, and end pieces 19 connecting the side bars. Handle supporting sections 20 project inwardly into the opening formed by the side bars and end pieces, and handle positioning sections 21 project from opposite ends of the plate. The sections 20 have handle locating lugs 22 projecting from their ends and holes 23 to form sockets to receive the outwardly bent ends of a connecting piece extending from a handle, and as illustrated in dotted lines in Figures 5 and 6 of the drawings. The positioning section is formed with positioning prongs 24—25, the former being

located at the outer sides of the section and the latter being located at the inner sides of the section and provided with fingers 26 extending toward each other, and as shown in Figure 7 of the drawings. Clips 27 also project into the central opening at the center thereof.

In forming the bracket the side bars 17 are bent at substantially right angles to the plane of the plate, grooves being formed therein to receive the members 9. The clips 18 are also bent to form grooves to receive the channel members 8, and the clips 27 are bent to form grooves to receive the channeled members 9. It will thus be seen that tie pieces and spacers are embodied in this bracket construction as well as in the members 14. The handle supporting sections 20 are bent downwardly at substantially right angles to the end pieces 19 and the handle positioning sections are bent to overlie the end pieces 19. The locating lugs 22 are bent into the position shown in Figures 5 and 6 of the drawings to form lugs to receive pivots 28 of a handle connector shown in dotted outlines in Figures 5 and 6 of the drawings, thus locating the pivots opposite the holes 23 into which said pivots move by a springing action of the connector. These lugs may also act to support the pivots in addition to their support in the holes 23. The fingers 26 are bent downwardly into the position shown in Figures 5 and 6 of the drawings, the arms 30 of the spring connector being received against these fingers when said arms are in the notches 31, and thus take a part of the wear of said arms upon said notches, as it has been found that in use the connector will more frequently be located in these notches than in the notches 32 at opposite sides of the notches 31, it being understood that the spring arms of the connector may be compressed toward each other to release them from any of the notches and the connector being then swung on its pivot in the holes 23 said arms may be located in any of the other notches.

While the entire brush, including the brush frame and the bracket for securing a handle thereto, has been illustrated and described herein, my invention resides in the construction of the brush frame only and does not embody the details of construction of the bracket for securing the handle.

In accordance with the provisions of the patent statutes I have described the principles of operation of my invention, together with the device which I now consider to represent the best embodiment thereof; but I desire to have it understood that the device shown is only illustrative and that the invention as contemplated by the appended claims may be carried out by other means and applied to uses other than those above set out.

I claim—

1. A brush including a frame formed of a

plurality of frame members, one located within the other and each comprising an independent unit with brush material secured therein and projecting in one direction therefrom, spacers extending across said members and secured thereto to hold them in spaced relation, said spacers being mounted and located widely apart to provide substantially open frame work of said units and means for securing the handle to the back of said frame. 75

2. A brush including a frame comprising a plurality of frame members each having its ends joined to form an endless structure, one of which structures is located within the boundaries of another, said members being substantially evenly spaced from each other throughout their length, and spacers extending across and secured to said members intermediate their ends to hold them in spaced relation, means for securing a handle to the back of said frame, and brush material projecting from the front edge of said members. 85

3. A brush including a frame formed of a plurality of endless frame members, one located within the boundaries of another, brush material projecting from an edge of each of said frame members, spacers extending across said members and secured thereto to hold them in spaced relation, and means for securing a handle to the back of said frame. 90

4. A brush including a frame formed of channeled members of endless construction of oblong shape and located one within the boundaries of another, brush material projecting from open edges of said members, the opposite edges of said members being closed, spacers having grooves along their lengths within which to receive said members to evenly space them apart, said spacers extending across said frame members near opposite ends of the frame, and a bracket secured to a plurality of lengths of said frame members to space them at the lengthwise center of the frame, said bracket having means to receive a handle. 100
